GUSTAV A. KRAMER, OF CONCORD, CALIFORNIA, ASSIGNOR, BY MESNE ASSIGNMENTS,
TO SIMPLEX REFINING COMPANY, OF SAN FRANCISCO, CALIFORNIA, A CORPORA-
TION OF CALIFORNIA.

PROCESS OF PRODUCING LUBRICATING OILS.

Application filed May 9, 1925. Serial No. 29,047.

My invention relates to the art of producing lubricating oils from petroleum. The term "petroleum" as used herein includes not only crude petroleum but also various petroleum derivatives produced by distillation or otherwise.

It is an object of my invention to provide a process by which petroleum may be refined to produce lubricating oils which are heavier than those produced by means of ordinary vacuum distillation.

It is a further object of my invention to provide a process by which I can produce petroleum lubricating oils which are free from undesirable products which would tend to lower the initial commercial value of the oil or cause a slow deterioration thereof subsequent to its production.

It is a further object of my invention to provide a process by which it is possible to use steam for the production of lubricating oils at very low absolute pressures, and in which, even at these low absolute pressures, the condensation of the steam and other vapors may be accomplished by using cooling water of readily available temperature. The term "cooling water of readily available temperature" as used herein is intended to designate cooling water produced by cooling towers or spray ponds in the temperate zone.

It is a further object of my invention to provide a process for the production of lubricating oils from petroleum in which the distillation is accomplished by the use of steam, but in which the consumption of steam is kept below that obtained in any previously known steam distillation process.

The annexed drawing represents diagrammatically an apparatus by which the invention may be carried on, the individual pieces of apparatus being old in the art and being represented partly in section to better illustrate their internal structure.

This apparatus may conveniently consist of the following main members: A tubular preheater 1, a still 2, a lubricating oil condenser 3, a vapor cooler 4, an ejector 5, a cracked products condenser 6, a lubricating oil cooler 7, a separator 8, and a steam condenser 9. The greater portion of this apparatus is designed to operate under vacuum and is so constructed as to resist external pressure.

The preheater 1 consists of any convenient form of preheating device, that shown consisting of a coil of pipe 10 carried in a furnace 11 heated by any convenient means, not shown. The oil to be preheated is fed into the coil 10 through a pump 12 and the heated oil is fed through a pipe 13 into the still 2. A valve 14 may be placed in the pipe 13 for holding the oil in the coil 10 under some slight pressure to prevent the formation of vapors and foaming in the preheater and also for shutting off the preheater 1 from the still 2.

The still 2 may be of any convenient form, that shown consisting of a tubular body 15 having a dome 16. A perforated steam pipe 17 is placed in the bottom of the still 2, through which steam may be blown through the charge of oil therein, the steam pipe 17 being provided with a valve 18. The still 2 may be set in a furnace 19 which is heated by means of a burner 20 controlled by a valve 21. Heat insulation 22 surrounds the tubular still 2 and the dome 16. Oil vapors and steam are carried from the dome 16 through a pipe 23 into the lubricating oil condenser 3.

The lubricating oil condenser chosen to illustrate the invention comprises a tubular shell 24 having heads 25 at either end thereof. Tubes 26 are provided between the heads 25, air being blown through these tubes through a pipe 27 from a blower 28. A damper or air valve 29 is provided in the pipe 27 for regulating the flow of air therethrough. The lubricating oil condenser 3 is also provided with an insulating jacket 30 to prevent heat losses therefrom.

Any lubricating oil condensed in the condenser 3 is passed through a siphon or loop 31 into the lubricating oil cooler 7, which comprises a tank 32 through which water may be circulated by means of pipes 33 and 34. The cooler also comprises a worm 35 set in the water of the tank 32, this worm extending through the bottom of the tank 32 and connecting with a pipe 36 having a valve 37. The pipe 36 is connected to a lubricating oil pump 38.

Any uncondensed gases or vapors passing through the lubricating oil condenser 3 are delivered through a pipe 39 to the vapor cooler 4. This comprises a tank 40 through which water may be circulated by means

of pipes 41 and 42. In the tank 40 is a worm 43 which connects through a pipe 44 with the ejector 5.

The ejector 5 is of any well known form, being fed with steam from a pipe 45 through a valve 46. The ejector acts to withdraw gas and vapor from the pipe 44 and force it at a higher pressure through a pipe 47 into the cracked products condenser 6.

The cracked products condenser 6 comprises a tank 48 through which water may be circulated by means of pipes 49 and 50. Situated in the tank 48 is a worm 51 into which the vapors and uncondensed gases from the ejector 5 are fed, the worm 51 connecting through a pipe 52 with the top of the separator 8.

Any liquid condensed in the condenser 6 is separated in the separator 8 and delivered through a valve 53 to a cracked products pump 54.

Uncondensed gases or vapors pass through a pipe 55 into the steam condenser 9, which may consist of a tubular member 56 having a water spray 57 fed through a pipe 58 having a valve 59. Water is sprayed downwardly through the interior of the member 56, and this water and any condensates formed therein are delivered through a pipe 60 having a valve 61 to the water pump 62. Air and other uncondensable gases collecting inside the member 56 are withdrawn through a pipe 63 having a valve 64 by a gas pump 65.

For convenience I provide a vacuum gage 66 on the still 2 and a similar vacuum gage 67 on the steam condenser 9. A thermometer 68 is provided for measuring oil temperature in the still 2, and thermometers 69 and 70 are provided on the inlet and outlet sides of the lubricating oil condenser 3. Other gages and indicating or recording devices may be supplied if desired.

The method of operation of my invention is as follows:

I prefer to use as a charging stock petroleum from which the more volatile fractions have been removed. I have found that in the practical operation of the invention an oil from which all fractions boiling below 600° F. at atmospheric pressure have been distilled is quite suitable for my purpose. The charging stock is fed through the pre-heater 1 and is delivered into the still 2, preferably at a temperature near that at which it is desired to start the distillation. The valve 14 is closed as soon as the still 2 is charged. The valves 46, 37, 53, 59 and 18 being closed, the absolute pressure within the apparatus may be brought down to the desired point by operating the air pump 65 which pumps off the air and vapors to any desired degree. Heat may be applied to the charging stock in the still 2 by means of the

burner 20 and its temperature readily determined by the thermometer 68.

In practice I may elect, for example, to operate the still 2 at an absolute pressure of 5 millimeters of mercury, as indicated by the gage 66, and the pump 65 is utilized to produce this high vacuum or low absolute pressure initially. Steam is admitted whenever desired through the pipe 17 by opening the valve 18 so that a mixture of oil vapors and steam leaves the still 2 through the pipe 23. In practice I may supply, for example, sufficient steam so that the vapor passing through the pipe 23 contains 10 per cent of its own weight of steam, the steam at the temperature and pressure employed having a volume of about twenty times that of the oil vapors carried through the pipe 23. The partial pressure of the oil vapors in the still 2 with a total pressure of 5 millimeters is therefore maintained at about 5/20ths of this figure, or about 0.4 millimeter of mercury. At this extremely low partial vapor pressure the oil vaporizes readily and there will be distilled from the petroleum a very superior grade of lubricating oil if the petroleum is heated to temperatures above 300° F.

I have found that however carefully petroleum may be initially refined to produce the charging stock which I intend to use, and however carefully the apparatus described herein may be operated, there will inevitably appear in the still 2 certain cracked products. These products are formed by the breaking up of the hydrocarbon molecules of the petroleum into cracked molecules having a smaller number of carbon atoms. These cracked molecules are unsaturated and have a lower boiling point than the petroleum molecules from which they are formed. Having a lower boiling point they pass very readily as a vapor through the pipe 23, and being unstable they tend to give any lubricating oil in which they are allowed to condense certain very undesirable qualities, such as a bad color and odor, and a tendency to produce resin-like substances. I have found that by the use of steam in the still 2, the amount of these cracked products produced can be minimized due to the low partial vapor pressure and the consequent low temperature at which distillation occurs.

I find, however, that it is impossible to prevent the formation of a small percentage of these undesirable compounds even if amounts of steam far in excess of those above specified are used. Some of these undesirable cracked products may of course polymerize in the still 2, or later, to form other compounds.

It is a particular object of my invention to provide means for preventing undesirable compounds from appearing in the lubricating oil. This can be accomplished, for ex-

ample, by the use of the condenser 3 which provides a very efficient method of temperature regulation. By blowing air from the pump 28 through the tubes 26, I am able to cool the oil vapors surrounding these tubes to any desired degree, and by a manipulation of the valve 29 I can readily change the degree of cooling produced in the condenser 3. I find that if the temperature-drop of the vapors in passing through the condenser 3 is kept very small, it is possible to practically eliminate any condensation of undesirable products.

In practice I may operate my apparatus with a drop in temperature in the condenser 3 of from 10° F. to 50° F. so that the vapors leaving the oil condenser 3 through the pipe 39 are at a temperature as indicated by the thermometer 70 of only from 10° to 50° F. below the temperature of the vapors entering this condenser through the pipe 23 as indicated by the thermometer 69. By so operating I am able to deliver to the siphon 31 a lubricating oil which is substantially free from undesirable products. The siphon 31 is kept filled with this oil and acts as a seal to prevent any vapors from passing into the cooler 7 and being condensed therein. The lubricating oil which is delivered to the cooler 7 at a temperature slightly below that maintained in the still 2 is cooled and is delivered at a lower temperature through the pipe 36 and valve 37, being withdrawn through the pump 38 and delivered to suitable storage, not shown.

The vapors passing through the pipe 39 are then very materially cooled in the cooler 4. This cooler is supplied with cooling water and may produce a drop in temperature of several hundred degrees. The principal object of the cooler 4 is to reduce the volume of the steam and other vapors and thus reduce the steam consumption in the ejector 5.

The ejector 5 is a convenient device for moving large volumes of vapor at a low increase in pressure. Steam is admitted thereto from the pipe 45 by opening the valve 46. In practice it may be called upon to raise the pressure on the vapors from 5 millimeters of mercury to approximately 50 millimeters of mercury. The steam and other vapors are then passed at this higher pressure into the condenser 6, in which the undesirable products tend to condense out. Some of these undesirable products may, in fact, start to condense in the condenser 4 and are then delivered by the ejector into the condenser 6.

The fluids leaving the condenser 6 through the pipe 52 are preferably at such a temperature that no substantial condensation of steam has occurred, but that substantially all of the undesirable or cracked products have been condensed so that they can be separated

in the separator 8 and withdrawn through the valve 53 by means of the pump 54. These undesirable products consist largely of cracked, unsaturated, and unstable hydrocarbons which, however, have certain uses and some commercial value. They are delivered from the pump 54 to suitable storage, not shown.

The vapors passing through the pipe 55 consist almost wholly of steam with which is mixed a small amount of air and some other undesirable gases. In the steam condenser 9 the steam is cooled by the water jet 57 by means of water delivered through the pipe 58 and valve 59, the condensates being removed through the valve 61 by means of the pump 62. The air and uncondensed gases are withdrawn through the pipe 63 and the valve 64 by the pump 65.

My invention differs from previous attempts to produce lubricating oil by means of steam distillation under vacuum in that I am able to obtain an absolute pressure in the still 2 which is far below the vapor pressure of the available cooling water since steam would have to be cooled below 32° F. to condense at an absolute pressure of 4.6 millimeters of mercury. If, therefore, I attempted to use pressures of 5 millimeters of mercury or below in the still 1 and attempted to condense the steam at such pressures, it would be necessary for me to provide refrigerating means for this condensation.

By utilizing the ejector 5 I am able to increase the absolute pressure of the steam before its condensation to a point at which the steam can be readily condensed by ordinary condensing equipment, such as is used in steam power plants, and by the use of cooling water at a temperature which can ordinarily be easily obtained in temperate climates throughout the year by well known means.

My invention also differs from previous vacuum processes using steam. I maintain the absolute total pressure in the still sufficiently low to obtain low partial oil vapor pressures without the injection of large quantities of steam. This is quite necessary if an economical process is to result, as steam is quite expensive, and by keeping the consumption of steam down to 10 per cent by weight of the lubricating oil produced I am able to refine lubricating oils cheaply and efficiently.

The steam also plays an important part in preventing the condensation of the undesirable products with the lubricating oil. These undesirable products are present in the vapors passing through the pipe 23 in comparatively small quantities, it being possible to maintain this percentage well below 1 per cent of the total lubricating oil produced. The partial vapor pressure of these

undesirable fractions is therefore very low as they enter the oil condenser 3. They therefore do not tend to condense readily at this low partial vapor pressure. Were 5 the steam absent the partial vapor pressure on the undesirable fractions would still be low at the point where they entered the oil condenser 3, but inasmuch as substantially all of the lubricating oil vapors are con- 10 densed in the oil condenser 3 the partial vapor pressure on the undesirable vapors in the oil condenser 3 would be substantially the total pressure. This great increase in vapor pressure of the undesirable compounds 15 would cause them to condense more readily and considerable quantities would appear in the lubricating oil.

By mixing with the oil vapors a large volume of steam which is not condensed in 20 the condenser 3, I am able to maintain an extremely low partial vapor pressure on the undesirable vapors which do not condense, and which are therefore readily carried over with the steam. The steam acts also as a 25 diluting agent for the undesirable compounds to prevent their absorption in the lubricating oil.

I claim as my invention:

1. A method of distilling petroleum to 30 produce lubricating oils which comprises: producing a mixture which contains lubricating oil vapors, steam and fixed gases at a primary pressure below atmospheric pressure, this pressure being so low that steam 35 cannot be condensed thereunder at available cooling water temperatures; cooling said mixture to a temperature at which substantially all the lubricating oil vapors will condense without substantial condensation of 40 said steam; segregating the lubricating oil so condensed; increasing the pressure on the remaining constituents of said mixture to a pressure substantially below atmospheric 45 pressure but at which steam readily condenses at available cooling water temperatures; cooling said other constituents to a temperature at which said steam is readily 50 condensed; segregating the water so produced; and segregating and removing any vapors or gases remaining after the condensation of said steam.

2. A method of distilling petroleum to produce lubricating oils which comprises: producing a charging stock by distilling from a 55 raw material all constituents which are more volatile than the lubricating oil which it is desired to obtain; heating said charging stock to produce a mixture which contains lubricating oil vapors, steam and fixed gases 60 at a primary pressure below atmospheric pressure, this pressure being so low that steam cannot be condensed thereunder at available cooling water temperatures; cooling said mixture to a temperature at which substantially 65 all the lubricating oil vapors will con-

dense without substantial condensation of said steam; segregating the lubricating oil so condensed; increasing the pressure on the remaining constituents of said mixture to a pressure substantially below atmospheric 70 pressure but at which steam readily condenses at available cooling water temperatures; cooling said other constituents to a temperature at which said steam is readily 75 condensed; segregating the water so produced; and segregating and removing any vapors or gases remaining after the condensation of said steam.

3. A method of distilling petroleum to produce lubricating oils which comprises: producing a mixture of lubricating oil vapors, undesirable vapors, steam and fixed gases; condensing the lubricating oil vapors at a pressure so low that steam cannot be condensed therefrom at available cooling water 80 temperatures, sufficient steam being supplied to prevent the simultaneous condensation of said undesirable vapors; and subsequently increasing the pressure on said undesirable 85 vapors, steam and fixed gases to a point at 90 which said steam is readily condensed at available cooling water temperatures.

4. A method of distilling petroleum to produce lubricating oils which comprises: producing a mixture of lubricating oil 95 vapors, undesirable vapors, steam and fixed gases; condensing the lubricating oil vapors at a pressure so low that steam cannot be condensed therefrom at available cooling water temperatures, sufficient steam being supplied to prevent the simultaneous condensation of said undesirable vapors; cooling the undesirable vapors, steam and fixed gases to reduce their volume; and subsequently increasing the pressure on said undesirable 100 vapors, steam and fixed gases to a point at 105 which said steam is readily condensed at available cooling water temperatures.

5. A method of producing lubricating oils from petroleum which comprises: distilling a charging stock in the presence of steam at an absolute pressure lower than the vapor pressure of the available cooling water; condensing the oil vapors at substantially this same pressure; and compressing the steam to a pressure at which it can be condensed by 110 said cooling water.

6. A method of producing lubricating oils from petroleum which comprises: distilling a charging stock in the presence of steam at an absolute pressure lower than the vapor pressure of the available cooling water; condensing the oil vapors at substantially this same pressure and at a temperature not more than 100° F. below the temperature of the vapors produced; and compressing the steam to a pressure at which it can be condensed by 115 said cooling water.

7. A method of producing lubricating oils from petroleum which comprises: distilling 120

- a charging stock in the presence of steam at an absolute pressure lower than the vapor pressure of the available cooling water; condensing the oil vapors at substantially this same pressure and at a temperature not more than 50° F. below the temperature of the vapors produced; and compressing the steam to a pressure at which it can be condensed by said cooling water.
- 10 8. A method of producing lubricating oils from petroleum which comprises: distilling a charging stock in the presence of steam at an absolute pressure lower than the vapor pressure of the available cooling water; condensing the oil vapors at substantially this same pressure and at a temperature not more than 20° F. below the temperature of the vapors produced; and compressing the steam to a pressure at which it can be condensed by said cooling water.
- 15 9. A method of producing petroleum lubricating oils substantially free from cracked products, which comprises: distilling said petroleum with unavoidable production of cracked vapors; condensing the lubricating oil vapors in the presence of sufficient steam to prevent the condensation of said cracked vapors and at an absolute pressure sufficiently low to prevent the condensation of said steam; and thereafter condensing said steam at a higher pressure which is substantially below atmospheric pressure.
- 20 10. A method of producing petroleum lubricating oils substantially free from cracked products, which comprises: distilling said petroleum with unavoidable production of cracked vapors; condensing the lubricating oil vapors in the presence of sufficient steam to prevent the condensation of said cracked vapors and at an absolute pressure sufficiently low to prevent the condensation of said steam; and thereafter condensing said steam and cracked vapors at a higher pressure which is substantially below atmospheric pressure.
- 25 11. A method of distilling lubricating oils from petroleum which comprises: removing lubricating oil by condensation from a space containing lubricating oil vapors and steam at high temperature and low absolute pressure; and transferring the uncondensed steam into a space of lower temperature and higher absolute pressure in which said steam is condensed.
- 30 12. A method of producing from petroleum lubricating oils substantially free from undesirable components, which comprises: removing lubricating oil by condensation from a space containing lubricating oil vapors, the vapors of an undesirable component and steam, said condensation taking place at a sufficiently high temperature and low pressure to prevent substantial condensation of said steam and vapors of said undesirable component; and transferring said
- 35 steam and vapors of said undesirable component to a second space maintained at a sufficiently lower temperature and higher pressure to permit the condensation of said steam therein.
- 40 13. A method of producing lubricating oils from petroleum which comprises: distilling petroleum in the presence of steam at a sufficiently low total absolute pressure to produce lubricating oil vapors mixed with steam without the production of substantial amounts of cracked products; reducing the temperature of the resulting mixture of steam and oil vapors, without substantial change in said absolute pressure, to a sufficient degree to condense therefrom the desired lubricating oil fraction; and removing the uncondensed portion of the mixture to a space of higher absolute pressure wherein the steam is condensed.
- 45 14. A method as in claim 13 in which the pressure on the mixed vapors prior to and during the condensation of lubricating oil therefrom is sufficiently low to prevent the condensation of steam at available cooling water temperatures.
- 50 15. A method as in claim 13 in which the pressure on the steam during condensation thereof is sufficiently high to permit condensation of said steam at available cooling water temperatures.
- 55 16. A method as in claim 13, in which the temperature at which said lubricating oil is condensed is not low enough at the pressure used during said condensation to cause appreciable condensation of undesirable products.
- 60 17. A process of treating mineral oils, which comprises: producing a mixture of vapors from a suitable charging stock under a low absolute pressure; cooling said mixture of vapors to a sufficient degree to condense therefrom a certain portion thereof; increasing the absolute pressure on the remaining vapors to a value which is still considerably less than atmospheric pressure; and subjecting said remaining vapors to a further condensation.
- 65 18. A process of treating mineral oils to produce therefrom certain products, which comprises: producing a mixture of oil vapors and steam at a low absolute pressure; cooling said mixture to such a degree that a desired oil fraction condenses therefrom without substantial condensation of water vapor; increasing the absolute pressure on the uncondensed vapors to a degree which is still below atmospheric pressure; and subjecting said vapors at said higher pressure to a further condensing action.
- 70 19. A process of treating mineral oils to produce therefrom certain products, which comprises: producing a mixture of oil vapor and steam at a low absolute pressure; cooling said mixture to such a degree that

- a desired oil fraction condenses therefrom without substantial condensation of water vapor and without substantial increase in said absolute pressure; increasing the absolute pressure on the uncondensed vapors to a degree which is still below atmospheric pressure; and subjecting said vapors at said higher pressure to a further condensing action.
10. A process of producing a lubricating oil from a suitable charging stock, which comprises: heating the charging stock to produce a complex mixture of vapors therefrom under low absolute pressure; cooling said complex mixture of vapors under substantially the same pressure to such a degree that the desired lubricating oil fraction condenses therefrom; increasing the pressure on the uncondensed vapors to a value still con-

siderably lower than atmospheric pressure; ²⁰ and subjecting said uncondensed vapors at said higher pressure to further condensation.

21. A process of producing lubricating oils, which comprises: heating a suitable charging stock in the presence of water vapor and at a low absolute pressure to produce a mixture of vapors; cooling said vapors to a sufficient degree to condense therefrom a desired lubricating fraction; increasing the pressure on the uncondensed vapors ²⁵ to a value which is below atmospheric; and subjecting said vapors at said higher pressure to a further condensation.

In testimony whereof, I have hereunto set my hand at Martinez, California, this ³⁰ 1st day of May, 1925.

GUSTAV A. KRAMER.
